UNITED STATES PATENT OFFICE.

FRANK E. BESSLER, OF AKRON, OHIO.

MOVABLE STAIRWAY.

Application filed September 15, 1925. Serial No. 56,545.

The device forming the subject matter of this application is of that general type in which a stairway is mounted slidably on a vertically swinging panel, and the invention 5 aims to provide novel means for controlling the movements of the stairway and the panel, novel means being provided for holding the stairway slidably on the panel.

It is within the province of the disclosure 10 to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes 15 in the precise embodiment of the invention herein disclosed, may be made within the scope of what is claimed without departing from the spirit of the invention.

In the accompanying drawings:—

Figure 1 shows in side elevation, a device 20 constructed in accordance with the invention, the panel being swung downwardly, and the stairway being slid downwardly on the panel; Figure 2 is a fragmental elevation showing how sundry parts cooperate when the stairway is slid backwardly on the panel; Figure 3 is a section on the line 3—3 of Figure 2; Figure 4 is a section on the line 4—4 of Figure 1; Figure 5 is a section on the line 5—5 of Figure 1; Figure 6 is a section on the line 6—6 of Figure 1; Figure 7 is a section through one of the spring drums; Figure 8 is a perspective view showing one of the retainers and attendant parts.

The numeral 1 marks a support, which 25 may be the ceiling of a room, the support having an opening 2. The numeral 3 marks a panel which is hinged at 4 to the support 1 at one end of the opening 2, for vertical swinging movement. The numeral 40 designates any suitable means whereby an operator 30 may swing the panel 3 downwardly into the position shown in Figure 1.

An angle plate 50 is secured at 51 to the support 1, at one end of the opening 2. Horizontally spaced angle brackets 52 (Figure 4) are secured at 54 to the angle plate 50. The brackets 52 have outstanding arms 53. Shafts 55 are mounted in the arms 53 of the angle brackets 52. Supporting wheels 56 are mounted on the shafts 55. The supporting wheels 56 are located inwardly of

the arms 53. Shafts 57 are mounted in the arms 53 of the brackets 52. Pulleys 58 are journaled on the shafts 57. The pulleys 58 are located outwardly of the arms 53.

Lower bearing brackets 6 are carried by the panel 3. Securing elements 7 are mounted in the brackets 6 near to their upper ends. Retainer blocks 8 are mounted pivotally on the inner ends of the securing elements 7 and are located inwardly of the brackets 6. The securing elements 7 project, as shown in Figure 3, outwardly of the brackets 6. A shaft 9 is mounted in the brackets 6. Supporting wheels 10 are journaled on the shaft 9 and are located inwardly of the bearing brackets 6. The wheels 10 have projecting flanges 11 at their inner ends. Cotter pins 12 hold the wheels 10 in place on the shaft 9. Pulleys 14 are journaled on the shafts 9 outwardly of the brackets 6. The pulleys 14 are retained in place by cotter pins 15.

The numeral 16 designates a stairway slidably mounted on the panel 3. The stairway 16 comprises stiles 17 and treads 18. The uppermost tread is marked by the numeral 19 and is wide enough to bridge the space between the upper end of the stairway 16 and the adjacent portion of the support or ceiling 1, when the parts are arranged as shown in Figure 1. The uppermost tread of the stairway 16 is held in place by brackets 63 provided on their edges with outwardly extending depending stops 64, one of which is shown clearly in Figure 1. The stairway 16 carries a fixed hand-rail 21. The stiles 17 of the stairway 16 ride at their lower edges on the supporting wheels 10 and 56, and the inner surfaces of the stiles are engaged by the flanges 11 of the wheels 10 to hold the stiles as shown in Figure 6.

Hangers 59, in the form of plates are provided. The hangers 59 are mounted for swinging movement, vertically, on the shafts 55 of the arms 53 of the angle brackets 52. The hangers 59 are located between the supporting wheels 56 and the arms 53 of the angle brackets 52, as shown in Figure 4. A cross tie 60 connects the hangers 59, the upperstanding ends 61 of the cross tie being connected to the hangers. Retainer blocks 62 are attached to the inner surfaces of the hangers 59. In the outer surfaces of the stiles 17 of the stairway 16, longitudinal guide grooves 22 are formed. The retainer blocks 8 and 62 are received slidably in the guide grooves 22. The retainer blocks are

called by that name, because they retain the stiles 17 of the stairway 16 on the supporting wheels 10 and 56 for sliding movement. Since the retainer blocks 8 are mounted pivotally on the securing elements 7, the retainer blocks will not bind in the grooves 22, but will accommodate themselves readily to the grooves, even though the stairway 16 may not be disposed exactly parallel to the panel 3. When the stairway 16 is slid downwardly on the panel 3, as in Figure 1, the stops 64 cooperate with the upper edges of the hangers 59, to limit the downward sliding movement of the stairway on the panel. Supports 24 are mounted on the stiles 17 of the stairway near to the lower end of the stairway. Latches 25 are mounted pivotally intermediate their ends on the supports 24 and are adapted to cooperate with the securing elements 7 of the brackets 6, when the stairway 16 is slid upwardly, to hold the stairway in place, detachably, against downward sliding movement. When the stairway is slid upwardly, as aforesaid, into the position of Figure 2, the supports 24 abut against the upper ends of the brackets 6 and stop the upward movement of the stairway, the latches 25 engaging with the parts 7 as hereinbefore explained. Bearings 26 are mounted on the support 1 at that end of the opening 2 which is remote from the hinge 4. A shaft 27 is carried by the bearings 26 and is held in place by set screws 28. Drums 29 are journaled on the shaft 27, outwardly of the bearings 26. Securing elements 30 hold the drums 29 on the ends of the shaft 27. Coiled springs 31 are located within the drums 29. The outer ends of the coiled springs 31 are connected at 32 to the drums 29, and the inner ends of the coiled springs are connected at 33 to the shaft 27. Flexible elements 34 are wound about the drums 29. From the drums 29, the flexible elements extend downwardly

about the pulleys 14 on the brackets 6, and, then, the flexible elements 34 are extended upwardly along the panel 3, and are engaged about the pulleys 58. From the last-specified pulleys, the flexible elements 34 are extended forwardly and downwardly along the stiles 17 of the stairway 16 and are connected to the stiles of the stairway by anchors 35.

In practical operation, when the panel 3 is swung downwardly and when the stairway 16 is slid downwardly with respect to the panel, the flexible elements 34 riding over the pulleys 14 and 58, will rotate the drums 29 and put the springs 31 under tension, the springs reacting to aid in the rearward or upward sliding movement of the stairway 16, and in the upward swinging movement of the panel 3, it being understood that when the occasion for the use of the stairway has passed, the stairway is slid rearwardly on the panel 3, and the panel is swung upwardly until it closes the opening 2 in the support 1.

Having thus described the invention, what is claimed is:

In a device of the class described, a support, an upper pulley carried for rotation on the support, a panel hinged to the support for vertical swinging movement, a lower pulley journaled on the panel, a spring-actuated drum mounted on the support, a stairway, means for mounting the stairway for sliding movement longitudinally of the panel, and a flexible element wound about the drum, the flexible element being extended downwardly around the lower pulley, rearwardly along the panel, about the upper pulley, and downwardly and forwardly along the stairway, and means for connecting the forward end of the flexible element to the stairway.

In testimony that I claim the foregoing as my own, I have hereto affixed my signature.

FRANK E. BESSLER.
